(57) **CLAIM**

The ornamental design for a foldable storage bin, as shown and described.

DESCRIPTION

FIG. 1 is a perspective view of a foldable storage bin in an unfolded, ready-to-use configuration of the present design.

FIG. 2 is a front view of the foldable storage bin;

FIG. 3 is a rear view of the foldable storage bin;

FIG. 4 is a right side view of the foldable storage bin;

FIG. 5 is a left side view of the foldable storage bin.

FIG. 6 is a top view of the foldable storage bin; and,

FIG. 7 is a bottom view of the foldable storage bin.

The broken lines illustrate stitching marks and form part of the claimed design.

The oblique lines in FIG. 1, FIG. 2, FIG. 3, and FIG. 6 indicate transparent materials for the applicable front panel, rear panel, and top panel (or cover) of the claimed foldable storage bin.
